UNITED STATES PATENT OFFICE

CHARLES W. TERWILLIGER, OF BROOKLYN, NEW YORK

CENTRIFUGAL DRIER

Application filed November 28, 1927. Serial No. 236,253.

This invention relates to centrifugal driers or extractors and more particularly refers to improvements in the construction of extractors such as used for drying clothes where a relatively high rate of speed must be used.

The primary object of this invention is to provide a novel and improved arrangement for yieldingly guiding the upper end of the upright shaft or spindle carrying the basket or container, said arrangement being designed so as to tend to continuously counterbalance the tendency of said shaft or spindle to deviate from the geometrical axis of rotation of its point of support due to uneven loading of the basket or container.

Another object of this invention is to provide practical and effective means for reducing or correcting vibrations such as are usually induced in the basket shaft or spindle in machines of the character mentioned, due to the practical impossibility of uniformly distributing the load within the basket or container.

A further object is to provide a novel and improved arrangement of yielding bearing for the upper part of the basket shaft or spindle of a centrifugal drying machine, adapted to be built as a complete unit in itself, and adapted to be mounted on machines already in use without entailing any material changes in their structure.

Other objects and advantages of the present invention will more fully appear as the description proceeds and will be set forth and claimed in the appended claims.

Centrifugal drying machines generally comprise a bowl or casing mounted on a vertical stand, a vertical shaft or spindle running centrally of said stand and projecting within the bowl, a basket or container carried by the upper end of said shaft within said bowl, and means for imparting rotation to the shaft.

The system is normally balanced, the center of gravity of the basket or container coinciding with the center of the shaft, but an unbalanced condition is created whenever the load is inserted into the basket,

because it is practically impossible to evenly distribute said load.

Due to this condition, considerable lateral stresses are created upon the shaft when the same is rotated at high speed; and the forces thus generated are of such an intensity that it has been found impractical to run the upper end of the shaft or spindle close to the basket through a bearing of the ordinary kind, without giving rise to destructive friction and wear.

Accordingly, it has become customary to mount the lower end of the shaft or spindle through an elongated bearing and to allow the upper end thereof to become deflected and to rotate in a conical path about the axis of gyration resulting from the load conditions and speed.

Attempts have been made towards correcting the ensuing vibration of the machine to a certain extent, for instance, by providing the upper end of the shaft or spindle with a rubber ring acting as a bumper absorbing part of the lateral shocks; but insofar as I am aware, no effective means has, as yet, been found to correct the tendency to vibration to any material extent, so that as a result dangerous conditions are still attached to the operation of these machines, increased power is needed for their operation and injurious wear is induced in the bearings due to lateral thrust of the shaft.

By virtue of my present invention, the lateral displacements of the shaft are largely prevented not at the expense of increased power consumption and wear, but by the deformation of elastic bodies acting as absorbers, arranged to exert their action in a continuous and practically uniform manner, creating but a limited amount of friction.

The arrangement is such that while the lateral displacements of the shaft are not entirely eliminated, they are reduced to a considerable extent so that no excessive demands are made upon the driving and the wearing parts of the machine and smooth running operation is assured.

My invention will be better understood by

referring to the accompanying drawings, in which:

5 Fig. 1 is a sectional view in elevation of a centrifugal extractor of a conventional type embodying my invention;

10 Fig. 2 is a fragmentary sectional view in elevation of the same in an enlarged scale, showing the general construction of my improved bearing;

15 Fig. 3 is a plan sectional view through line 3-3 of Fig. 2; and

20 Fig. 4 is a plan sectional view through the bearing shown in Figs. 2 and 3, illustrating the position of its various parts when the shaft is laterally displaced from 15 its normal center of rotation.

25 In the drawings, 10 designates the bowl or casing provided with a cover 11 and mounted on a stand 12. A bearing 13 extends upwardly from the base 14 of the stand, and in the same is rotatably mounted 20 a vertical shaft 15, the upper end of which projects within bowl 10.

30 Said upper end of the shaft carries an open top basket or container 16 which is usually perforated in order to permit the liquid extracted from the material inserted in the basket or container to be forced out by centrifugal force, to be collected at the bottom of the bowl. Rotation may be imparted to the shaft by means of a pulley 17, mounted at the lower part of said shaft, leaving a considerable length of shaft 15' between said pulley and the hub 18 of the 35 basket.

40 Ordinarily that part of the shaft which is designated by 15' is left free to obey the lateral impulses due to the unbalanced condition of the load; but as stated before, it is desirable in practice to limit as much as possible, the lateral displacements of the upper end of the shaft without however, creating new and antagonistic conditions which might nullify the advantages to be 45 gained or which might in fact be open to still more serious objections than the conditions originally existing.

50 I accordingly provide a specially designed yielding bearing for the upper end 55 of the shaft which is shown in the drawing as being mounted in a special frame 19 provided with depending brackets 20 adapted to be secured onto stand 12 in any suitable manner, for instance by means of screws 21 as shown.

55 Frame 19 consists of a lower plate 22, an upper plate 23 and four corner blocks 24, 25, 26, 27, joining the two plates, forming four passages 28, 29, 30, 31, at right angle 60 to one another between said upper and lower plates. The central portion of the frame is open from top to bottom, the opening thus formed being square in form as indicated at 32.

65 The center of said opening 32 coincides

with the junction point of the central lines of passages 28, 29, 30, 31, and the frame is so placed in position that said center coincides with the axis 33 of the lower end of the shaft and bearing 13.

70 A bushing for the upper end of the shaft is inserted through said opening 32, said bushing comprising a body portion 34 which is square in section and which is preferably somewhat longer than the distance between 75 the lower surface of plate 22 and the upper surface of plate 23, a flange 35 laterally extending from the upper end of said body portion, the outline of said flange being also preferably square, a threaded portion 36 80 downwardly extending from said body portion and a flanged nut 37 mounted on said threaded portion.

85 Said bushing has a central opening for the upper end of the shaft 15' and is normally mounted so as to maintain the shaft in a vertical position. However, the body portion 34 of the bushing is smaller in section than opening 32 so that when the bushing is centrally spaced with respect to frame 19, 90 a clearance 38 will remain all around between the sides of opening 32 and the sides of body portion 34.

95 Said body portion is also preferably provided with a peripheral groove 39 about 37 midway between flange 35 and flanged nut

100 Through each one of the passages 28, 29, 30, 31 are inserted resilient means for maintaining the bushing in its proper position, 100 said means preferably comprising a rubber block 40, a cap 41 for the inner end thereof, said cap being adapted to slide in a radial direction through its respective passage, and a rear plate 42 bearing against said rubber 105 block.

110 The outer end of each one of said passages 28, 29, 30, 31, is closed by a plate 43 which is secured to the frame by means of screws 44, and through the center of said plate 110 projects a screw 44 provided with a check nut 45, exerting pressure against plate 42 and maintaining therefore cap 41 in abutment against the opposite side of body portion 34.

115 Each cap 41 is preferably provided with a lug 46 projecting within groove 39, so that axial displacements of the bushing are prevented thereby. As stated before, the section of body portion 34 of the bushing is 120 smaller than opening 32, so that the upper part 15' of the shaft or spindle may be laterally displaced with respect to axis 33, unless said lateral displacement is prevented by other means. Screws 34 are so adjusted 125 that when the shaft is stationary, the pressures exerted by rubber blocks 40 against caps 41, neutralize one another, maintaining the center of alignment of the shaft. However, when the machine is rotated at 130

relatively high speed with an unbalanced load in the basket, the upper end of the shaft will acquire a tendency to lateral displacement, as before explained, and said tendency should be checked or to a certain extent counterbalanced without causing undue frictional resistance against the surface of the bushing.

By virtue of the arrangement described, 10 the bushing following the lateral displacements of the shaft bears in succession against one and then the other of caps 41, causing the compression of their respective rubber blocks 40, which thus act as absorbers of 15 the lateral thrust exerted by the shaft.

The relative arrangement of passages 28, 20 29, 30, 31, is such that the lateral displacements of the shaft are transmitted at all points to the rubber blocks, because when 25 the shaft is displaced directly in line with the central line of any one passage the bushing will bear against the cap sliding within said passage, and as soon as the transversal displacement of the shaft is directed at an 30 angle to said line, the bushing will simultaneously bear against said cap and also against the cap sliding through the next passage, until when the lateral displacement of 35 the shaft is directed at 90° to its former displacement the bushing bears entirely against the second cap, the central line of which is now in alignment with the direction of displacement of the shaft.

This point is clearly illustrated in Fig. 4 35 where the center 47 of the shaft is shown as being displaced from its normal axis 33 at 45° between cap 41' and cap 41''. In said position, as shown, the bushing bears simultaneously against the surfaces of both caps 40 so that both rubber block 40' and rubber block 40'' are compressed to the same extent. As the center 47 of the shaft continues 45 to rotate about axis 33, say for instance, in a counterclockwise direction, the pressure exerted against cap 41' decreases and the pressure exerted against cap 41'' increases, until the pressure exerted against cap 41' becomes nil and the pressure is borne entirely by cap 41''.

50 It will be observed that while lugs 46 prevent axial displacement of the bushing with respect to the frame, they do not prevent the lateral displacements of the bushing because groove 39 extends all around the bushing and its top and bottom surfaces can slide over the surface of said lugs.

As stated before, body portion 34 of the bearing is somewhat longer than the distance separating the lower surface of plate 60 22 from the upper surface of plate 23, so as to prevent wedging action by the inner surfaces of the flanges coming to bear against the outer surfaces of said plate when the bushing is displaced from its normal 65 position due to the lateral displacements of

the shaft; although it is obvious that only a very small clearance needs thus be provided between the inner surface of the plates and between the outer surface of the plates, because lateral displacements of the shaft are relatively so small when checked by the arrangement described, that they can practically be considered as taking place at right angle to the direction of axis 33.

70 For the device to be operative, it is important that opening 32 be larger than the section of body portion 34, because if such were not the case, the structure would become rigid instead of laterally yielding in character and the advantages of the arrangement would be lost. The adjusting screws 44 are also an important feature of the device, because by properly adjusting said screws it is possible to adjust the position of the shaft with the utmost accuracy; furthermore, it is also possible thereby to regulate the amount of pressure exerted 75 against the shaft.

80 Plates 43 can be removed with ease whenever desired, so that all the various parts can be removed, inspected or replaced at any time without interfering with the operation of the machine. If desired, the action of the rubber blocks could be supplemented or substituted by that of springs, but in 85 practice I have found the rubber blocks to provide a smoother and more satisfactory operation.

90 My improved arrangement can be embodied in the construction of new machines and in such case, frame 19 may be made integral with the stand or with the bowl portion of the structure, if desired; but if the device is made in the form of a complete detachable unit as shown, the same can 95 be readily installed in existing machines merely by properly designing the attaching means therefor.

100 The sliding caps must be so designed as to be inwardly movable to follow the displacements of the bushing, without interfering with one another, and this can be obtained either by making the width of said caps less than the width of the body portion 34 of the bushing, or else by making the width of the 105 caps equal to that of the said body portion 34 as shown, or larger and by cutting off the inner corners of said caps as shown at 48. In all cases the various elements of 110 which the structure is composed, must be 115 freely movable without interfering with the action of the other elements.

120 It is obvious that devices embodying my invention may be produced differing in many details from the arrangement shown 125 without departing from the inventive idea. For instance, while I have shown and described a bushing having four sides in combination with four yielding members bearing against said sides, it will be understood 130

that it is possible to use bushings having a different outline in combination with a different number of resilient members, as long as said members are not less than three in number.

5 The drawings should therefore, be understood as being intended for illustrative purposes only and not in a limiting sense. I accordingly reserve myself the right to 10 carry my invention into practice in all those ways and manners which may enter, fairly, into the scope of the appended claims.

I claim:

1. In a machine of the character specified, 15 the combination, with a bowl, a stand therefor, a normally vertical shaft, a basket within said bowl carried by said shaft, and a bearing for the lower end of said shaft, of a frame surrounding the upper part of said 20 shaft, a bushing for said shaft inserted through said frame, said bushing being provided with a peripheral groove, an opening through said frame allowing lateral displacement of said shaft and bushing, and 25 resilient means carried by said frame, and bearing against said bushing, said resilient means interlocking with said groove and being guided to move radially of the normal axis of rotation of said shaft.

30 2. In a machine of the character specified, the combination, with a bowl, a stand therefor, a normally vertical shaft, a basket within said bowl carried by said shaft, and a bearing for the lower end of said shaft, of a 35 frame surrounding the upper part of said shaft, a bushing for said shaft inserted through said frame, said bushing being provided with a peripheral groove, an opening through said frame allowing lateral displacement of said shaft and bushing, and 40 resilient means carried by said frame, and bearing against said bushing, said resilient means being guided to move radially of the normal axis of rotation of said shaft, said 45 resilient means being restrained from moving axially of said frame, and interlocking with said groove so as to prevent axial displacement of said bushing in relation to said means, while permitting lateral displacement thereof in relation to said frame.

50 3. In a machine of the character specified, the combination, with a bowl, a stand therefor, a normally vertical shaft, a basket within said bowl carried by said shaft, and a bearing for the lower end of said shaft, of a frame surrounding the upper part of said shaft, a bushing for said shaft inserted through said frame, said bushing having a 55 polygonal section and being provided with a peripheral groove, an opening through said frame allowing lateral displacement of said shaft and bushing, 60 passages radially extending through said frame opposite the side surfaces of said bushing, resilient members 65 slidably within said passages, bearing against said bushing and interlocking with said groove, means preventing axial displacement of said bushing in relation to said frame, and means for adjusting the pressure exerted by said resilient members against said bushing.

ing against said bushing, and interlocking with said groove.

4. In a machine of the character specified, the combination, with a bowl, a stand therefor, a normally vertical shaft, a basket within said bowl carried by said shaft, and a bearing for the lower end of said shaft, of a frame surrounding the upper part of said shaft, a bushing for said shaft inserted through said frame, said bushing having a 70 polygonal section and being provided with a peripheral groove, an opening through said frame allowing lateral displacement of said shaft and bushing, passages radially extending through said frame opposite the side surfaces of said bushing, and resilient members 75 slidably within said passages, bearing against said bushing, said resilient members interlocking with said groove, and being restrained from moving axially of said frame. 80

5. In a machine of the character specified, the combination, with a bowl, a stand therefor, a normally vertical shaft, a basket within said bowl carried by said shaft, and a bearing for the lower end of said shaft, of a frame surrounding the upper part of said shaft, a bushing for said shaft inserted through said frame, said bushing having a 90 polygonal section and being provided with a peripheral groove, an opening through said frame allowing lateral displacement of said shaft and bushing, and interlocking with said groove, passages radially extending through said frame opposite the side surfaces of said bushing, resilient members 95 slidably within said passages, bearing against said bushing, and means preventing axial displacement of said bushing in relation to said frame.

6. In a machine of the character specified, the combination, with a bowl, a stand therefor, a normally vertical shaft, a basket within said bowl carried by said shaft, and a bearing for the lower end of said shaft, of a frame surrounding the upper part of said shaft, a bushing for said shaft inserted through said frame, said bushing having a 100 polygonal section and being provided with a peripheral groove, an opening through said frame allowing lateral displacement of said shaft and bushing, passages radially extending through said frame opposite the side surfaces of said bushing, resilient members 105 slidably within said passages, bearing against said bushing and interlocking with said groove, means preventing axial displacement of said bushing in relation to said frame, and means for adjusting the pressure exerted by said resilient members against said bushing.

7. In a machine of the character specified, the combination, with a bowl, a stand therefor, a normally vertical shaft, a basket within said bowl carried by said shaft, and a bearing for the lower end of said shaft, of 110

a frame surrounding the upper part of said shaft, a bushing for said shaft inserted through said frame, an opening through said frame allowing lateral displacement of said shaft and bushing, passages radially extending through said frame opposite the surface of said bushing, a member slidably inserted through each passage, bearing against said surface, a rubber block pressing against said slidable member, and means for adjusting the pressure exerted by said rubber block against said member.
